US0D1093280S

(12) **United States Design Patent** (10) **Patent No.:** **US D1,093,280 S**
(45) **Date of Patent:** **** Sep. 16, 2025**

(54) **BATTERY**

(71) Applicant: **Workspor Ltd.**, Richmond Hill (CA)

(72) Inventors: **Jonathan Loudon**, Toronto (CA);
Steven Rossi, Vaughan (CA); **Jason Macdonald**, Toronto (CA)

(73) Assignee: **Workspor Ltd.**, Richmond Hill (CA)

(**) Term: **15 Years**

(21) Appl. No.: **29/870,410**

(22) Filed: **Jan. 25, 2023**

(51) **LOC (15) Cl.** **13-02**

(52) **U.S. Cl.**

USPC **D13/103**

(57) **CLAIM**

The ornamental design for a battery as shown and described.

DESCRIPTION

FIG. 1 is an upper perspective view showing a first embodiment of a battery;

FIG. 2 is a lower perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is an upper perspective view showing a second embodiment of a battery;

FIG. 10 is a lower perspective view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top plan view thereof; and,

FIG. 16 is a bottom plan view thereof.

(Continued)

The broken lines illustrate portions of the battery that form no part of the claimed design.

1 Claim, 16 Drawing Sheets
